DESIGN FOR A BOND AND POLICY FOLDER OR THE LIKE

Jean Moses, New York, N. Y.

Application April 7, 1944, Serial No. 113,171

Term of patent 7 years

(Cl. D59—8)

To all whom it may concern:

Be it known that I, Jean Moses, a citizen of the United States, and a resident of the city of New York, in the county of Kings and State of New York, have invented a new, original, and ornamental Design for a Bond and Policy Folder or the like, of which the following is a specification, reference being had to the accompanying drawing, forming a part thereof:

Fig. 1 is a perspective view of a bond and policy folder or the like, showing my new design in open position; and

Fig. 2 is a perspective view in reduced form, showing the folder of Fig. 1 in closed position.

I claim:

The ornamental design for a bond and policy folder or the like, substantially as shown.

JEAN MOSES.
